MUSIC PRINTING DEVICE

Guy A. Candelmo, West Aliquippa, Pa.

Application April 2, 1935, Serial No. 14,353

6 Claims. (Cl. 101—107)

This invention relates to printing devices and more particularly to a portable printing device for use in applying musical characters to blank sheets.

5 An object of this invention is to provide a device of this character which is so constructed that a composer or the like can readily impress the desired characters on the blank sheets of paper used for music in such a manner that the composer or person copying music will not be required to use a pen to draw out each character.

10 Another object of this invention is to provide a device of this character which is exceedingly simple in construction, embodying relatively few parts so that it will not readily get out of order and can be manufactured at a relatively small cost.

15 A further object of this invention is to provide in a device of this kind means to yieldably hold the impression cylinder with the raised characters thereon out of contact with the sheet of paper until the entire device has been forced in the direction of the papers.

20 A still further object of this invention is to provide in a device of this character a means whereby the desired ink may be applied, the ink being placed on a ribbon which is disposed in the yieldable impression member and normally maintained out of contact with the paper so that 25 the ribbon will not smudge the paper as the device is being moved along the surface of the sheet.

25 The above and various other objects and advantages of this invention will in part be described 30 in, and in part be understood from the following detail description of the present preferred embodiment, the same being illustrated in the accompanying drawings, wherein:—

35 Figure 1 is a detail side elevation of a device 40 constructed according to an embodiment of this invention showing the device in applied position;

45 Figure 2 is a similar view taken from the opposite side of the device from that shown in Figure 1;

50 Figure 3 is a sectional view taken on the line 3—3 of Figure 1;

55 Figure 4 is a plan view of the blank for the housing;

Figure 5 is a detailed perspective view, showing 60 the manner in which the device is used in impressing characters on a ruled sheet.

55 Referring to the drawings wherein like numerals of reference designate corresponding parts throughout the several views, the numeral 10 designates generally a housing which, in the pres-

ent instance, is constructed of a pair of side plates 11 and 12, connected together by means of a connecting wall 13. These side plates 11 and 12 are constructed in the form of fragmentary discs having a straight edge portion 14 and a resilient arm 15 provided with a bifurcated or forked end portion 16, secured to the wall 13 and extending below the straight portion 14 of the plates 11 and 12.

A cylinder 17 is disposed within the housing 10 and at one edge thereof is provided with a 10 plate 18, secured to a hub 19, journaled on a shaft or bolt 20, extending axially and transversely through the housing 10. This cylinder 17 comprises an impression cylinder and is provided on the peripheral edge thereof with raised characters 15 21 of the type used in the recording of music, it being understood that these characters 21 may be notes of different values and other indicia used in the recording of music.

A second housing, generally designated as 22, 20 is disposed at one side of the housing 10 being integral therewith and comprises a side plate 23, a bottom wall 24, and an end wall 25 which extends partially about the side wall 23. The end wall 25, as shown in Figure 4, is provided with 25 opposed lugs 26, one of which is adapted to engage in the side wall 11 of the main housing and the other adapted to engage in a notch 27, provided in the outer side wall 23. A ribbon 28 is mounted on a spool 29 which is rotatably carried 30 by the shaft or bolt 20 within the housing 22 and this ribbon 28 may be of the usual character used in typewriters, or the like.

The bolt 20 is provided at one end with a head 30 and a yieldable washer 31 is interposed between the head 30 and the side wall 12. The other end of the bolt or shaft 20 is threaded, as at 32, and a wing nut 33 is threaded onto this end of the bolt. By means of the wing nut 33, the desired tension may be placed on the two side 40 walls 11 and 12 so that the hub 19, secured to the plate 18, will be frictionally held against turning but permitted to turn when desired.

The ribbon 28 is threaded through a pair of aligned eyes 34, carried by the ends of the forked 45 or bifurcated portion 16. These eyes 34 are formed by bending the ends of the arms of the bifurcated portion backward to form loops or eyes. In this manner the ribbon 28 is disposed against the lowermost character or indicia 21 and 50 the eyes 34 hold the ribbon 28 off of the surface of the lined sheet 35.

In order to determine the position of the characters 21 on the periphery of the drum or cylinder 17, I have provided a substantially frustro- 55

- conical shaped member 36 which opens through the outer or forward side of the cylinder 17 and the inner surface of this member 36 is provided with indicia 21a of a type similar to the corresponding indicia 21 on the surface of the cylinder or drum 17. This member 36 may be formed as a separate part and then welded or otherwise secured to the flange or drum 17 or may be made integral therewith.
- 10 In the use and operation of this device, the drum 17 is turned so that the desired character 21 is disposed in confronting relation to that portion of the ribbon 28 disposed between the arms of the fork 16. The correct position and 15 the correct character may be determined by glancing at the indicia 21a on the inside of the frustro conical member 36. The forked member 16 is then placed on the surface of the sheet 35 and the housing 10 then grasped between a 20 thumb and forefinger whereupon the housing 10 is pressed toward the sheet 35, thus forcing the lowermost character 21 to contact with the ribbon 28 and impress this character 21 upon the surface of the sheet 35.
- 25 It will be understood that the eyes 34 and the ribbon 28 disposed within the eyes will serve as a guide means to facilitate placement of the characters in the desired position relative to the lines 37 provided on the sheet 35.
- 30 It is, of course, understood that various changes and modifications may be made in the details of construction and design of the above specifically described embodiment of this invention without departing from the spirit thereof, 35 such changes and modifications being restricted only by the scope of the following claims.
- I claim:—
1. A device as set forth comprising a housing having an opening in a wall thereof, a drum rotatable in the housing and having a portion 40 thereof projecting through said opening, raised characters on the periphery of the drum, a character inking means, a resilient arm carried by the housing for resiliently holding the characters away from a sheet of paper, and a pair of 45 guide eyes carried by said arm on opposite sides of said drum for holding the inking means in operative position.
2. A device as set forth comprising a housing having an opening in a wall thereof, a drum rotatable in the housing and having a portion 50 thereof projecting through said opening, raised characters on the periphery of the drum, a character inking means, a resilient arm carried by the housing for resiliently holding the characters 55 away from a sheet of paper, guide means for said inking means carried by said arm, and means for frictionally holding the drum against rotation.

3. A device as set forth comprising a housing having an opening in a wall thereof, a drum rotatable in the housing and having a portion thereof projecting through said opening, raised characters on the periphery of the drum, a character inking means, a resilient arm carried by the housing for resiliently holding the characters away from a sheet of paper, and means carried by said arm for holding said inking means in operative position.

4. A device as set forth comprising a housing having an opening in a wall thereof, a drum rotatable in the housing and having a portion thereof projecting through said opening, raised characters on the periphery of the drum, a character inking means, means for supporting said inking means at one side of the housing, said inking means including a flexible inking strip, a resilient arm carried by the housing for holding said characters away from a sheet of paper and 20 guide means for said strip carried by said arm.

5. A device as set forth comprising a housing having an opening in a wall thereof, a drum rotatable in the housing and having a portion thereof projecting through said opening, a shaft 25 carried by the housing and extending through said drum, raised characters on the periphery of the drum, a second housing disposed at one side of the first housing, a flexible inking strip, a spool disposed within said second housing and 30 rotatable on said shaft, said spool having a portion of said flexible strip wound thereabout, means engaging the shaft and the first housing to frictionally retard rotation of said drum and a plurality of raised characters disposed on the 35 periphery of the drum for exposure through said opening, said characters being engageable with said flexible strip whereby to impress the character on a sheet of paper.

6. A device as set forth comprising a housing 40 having an opening in a wall thereof, a drum disposed within the housing, a shaft carried by the housing and extending through the drum to rotatably support the drum in the housing, raised characters disposed on the periphery of the drum, 45 a second housing secured to said first housing at one side thereof, an inking means in said second housing, said inking means including a flexible strip extending outwardly through said second housing, means for frictionally retarding rotation of said drum, a resilient arm carried by the housing and a forked member integral with 50 said arm and provided at the ends thereof with eyes, said flexible strip being disposed loosely through said eyes and extending transversely of 55 the opening in the housing.

GUY A. CANDELMO.
